UNITED STATES PATENT OFFICE.

BERNARD WATERS, OF WINNIPEG, MANITOBA, CANADA.

PICTURE OR ADVERTISING EXHIBITOR.

Application filed April 27, 1920, Serial No. 377,093. Renewed November 22, 1922. Serial No. 549,475.

To all whom it may concern:

Be it known that I, BERNARD WATERS, of the city of Winnipeg, in the Province of Manitoba, Canada, have invented certain new and useful Improvements in Picture or Advertising Exhibitors, of which the following is the specification.

The invention relates to improvements in picture advertising frames and an object 10 of the invention is to provide a frame containing an endless ribbon or band having pictures or other display material thereon and with the band arranged so that it can be moved to expose selected pictures to view 15 and from time to time as occasion demands.

A further object is to provide a mechanism operable from the exterior of the frame for turning the band.

A further object is to construct the frame 20 so that it can be readily opened up to allow of the insertion and removal of the band.

With the above more important objects in view the invention consists essentially in a frame formed from a front and a back, 25 with the front containing a glass and the back, rollers at top and bottom, an endless band mounted on the rollers and having thereon a series of distinct spaced pictures or such like exhibit material and means 30 for manipulating the rollers to turn the band, the parts being arranged and constructed as hereinafter more particularly described and later pointed out in the appended claim, reference being had to the 35 accompanying drawing in which:—

Fig. 1 is a front view of a frame constructed in accordance with my invention.

Fig. 2 is a side view of the same.

Fig. 3 is a vertical sectional view at 40 3—3' Fig. 1.

Fig. 4 is an enlarged detailed vertical sectional view at 4—4' Fig. 2.

Fig. 5 is an enlarged detailed sectional view through one side of the back of the 45 frame.

Fig. 6 is a view of a band as it appears opened up and with the band approximately half scale as compared with Figures 1 and 3.

In the drawing like characters of reference indicate corresponding parts in the 50 several figures.

1 represents a containing frame having an ornamented front 2 and a box like back 3. The frame front is open centered and 55 is closed by a glass or such like transparent material 4 which is suitably mounted in

the frame. The front of the frame is hinged to the back as indicated at 5, thus permitting of easy access to the interior of the box which has the side next the front 60 open and the back, top, bottom and ends closed.

Immediately behind the glass 4 I locate a mat 6 which is provided with a number of similar spaced openings 7, this mat forming a setting for the various pictures which are exposed through the openings in the mat.

8 and 9 are a pair of upper rollers having their ends suitably mounted in the ends of 70 the box such as in a bearing plate 10. The rollers are located so that they are not exposed when the front of the frame is closed and they are supplied at their opposite ends with intermeshed gears 11 and 12 75 which cause the rollers to positively turn together. One of the rollers is fitted with an extending square stem 13 contained within an opening 14 reserved in the end of the box, and the stem is utilized for 80 turning the top rollers such as by using a socketed key.

15 is a bottom roller having the ends rotatably mounted in the lower part of the box behind the front of the frame, this 85 roller being parallel to the top roller. 16 is a band passing around the rollers 15 and 8 and contacting with the roller 9. Immediately behind the front part of the band I locate a cross partition 17 over which the 90 front side of the band is adapted to drag when the same is turned. Actually this partition is placed so that there is just nice clearance for the band between the partition and the mat 6, thus keeping the pictures exposed through the openings in a flat lying condition.

I desire that the bands be in the nature of strips having the pictures actually printed thereon in spaced relation so that when the band is turned and properly adjusted there will be in the present instance three pictures of the series exposed through the 95 openings 7.

In Figure 6 of the drawing the rectangular spaces 18 indicate the pictures or other material to be exposed and the margin or boundary line will preferably be a little smaller than the opening 7 in each case so that it forms a boundary line around the picture which can be seen through the opening.

In actual practice these bands or ribbons of pictures will probably have each series of pictures so that one can, by turning the band in the frame, expose the whole series by 5 turning with the key provided.

By providing the ribbons in this way I anticipate that it will be possible for one to buy a series of pictures on bands or ribbons and put them in his mechanical frame from 10 time to time as he desires.

One end of the band will be gummed as indicated at 19 so that all one has to do to put a band in the frame is to open the front, insert one end of the band between the top 15 rollers, turn the rollers and, after passing the inserted end down and around the roller 15, seal the ends together, care being taken that the band is drawn taut when sealed.

Obviously this frame can be made any 20 length desired, depending on the particular use which is made of it, whether for picture display purposes or for advertising purposes and the ribbons accordingly will have to vary in size to correspond with the size of 25 the frame.

What I claim as my invention is:—

The combination of a casing having a

transparent wall, a mat provided with a series of vertically spaced picture exhibiting openings supported directly behind said transparent wall in contact therewith, a partition within the casing spaced a slight distance behind said mat, said partition being of sufficient length to extend above and below the openings in the mat, an endless picture exhibiting band encircling said partition and having the forward run thereof guided between the partition and the mat, the rearward run thereof being guided between the partition and the wall of the casing opposite the transparent wall, a pair of upper rollers supported above the upper end of the partition and engaging opposite sides of said band, a lower roller supported beneath the lower end of said partition and engaging the band as it passes therebeneath, and means for simultaneously rotating both of said upper rollers to actuate the band.

Signed at Winnipeg, this 24 day of March 1920.

BERNARD WATERS.

In the presence of:—

GERALD S. ROXBURGH,

K. B. WAKEFIELD.
